UNITED STATES PATENT OFFICE

162,324

DOOR GRILLE OR THE LIKE

John E. Lindstrom, Aurora, Ill.

Application November 13, 1950, Serial No. 12,952

Term of patent 14 years

(Cl. D54—2)

To all whom it may concern:

Be it known that I, John E. Lindstrom, a citizen of the United States and a resident of the city of Aurora, in the county of Kane and State of Illinois, have invented a new, original, and ornamental Design for a Door Grille or the like, of which the following is a specification, reference being had to the accompanying drawings, forming part thereof.

Figure 1 is a plan view of a door grille or the like embodying my new design, and

Figure 2 is an edge view of the same.

I claim:

The ornamental design for a door grille or the like, as shown.

JOHN E. LINDSTROM.
